United States Patent Office

Des. 215,501
Patented Sept. 30, 1969

215,501

CALCULATING MACHINE

Alfons Boothby, Wilhelmshaven, Germany, assignor to
Olympia Werke AG, Wilhelmshaven, Germany

Filed Apr. 29, 1968, Ser. No. 11,669

Term of patent 14 years

Claims priority, application Germany Dec. 4, 1967

Int. Cl. D18—01

U.S. Cl. D64—11

Fig. 1

Fig. 2

Fig. 3

FIG. 1 is a perspective front view;
 FIG. 2 is a perspective rear view; and
 FIG. 3 is a perspective side view of my new design for
 a calculating machine.

The essential features of the design reside in the portions shown in full lines on the drawing, conventional keys and other elements being shown in broken lines for illustrative purposes.

I claim:

The ornamental design for a calculating machine, substantially as shown and described.
